UNITED STATES PATENT OFFICE

2,006,420

RIDING TOY

Clement E. Thompson, Freeport, Ill., assignor to
 Structo Manufacturing Company, Freeport,
 Ill., a corporation of Illinois

Application December 28, 1934, Serial No. 759,475

4 Claims. (Cl. 280—87.5)

This invention relates to riding toys and its principal object is to provide a wheeled toy having a movable riding seat flexibly but permanently attached to some portion of the toy structure, whereby the seat may be swung upward out of the way when the toy is to be loaded or unloaded.

The invention has particular reference to wheeled toys provided with a truck box, either fixed or of the dump type, over which the riding seat is placed. Heretofore in such toys the seat sometimes is made removable, and therefore is likely to be lost or mislaid and no provision has heretofore been made for properly locating the seat with respect to the steering handle with which such toys are usually equipped. Since many of these toys are intended for very small children, it is particularly desirable that the whole assembly be in the form of a unitary structure, so that the several movable parts thereof cannot become disconnected from the remainder. I have pivoted or hingedly connected the riding seat upon the body or some structural portion of the toy, whereby the seat may be raised above the truck box to permit the box to be loaded and unloaded and if a dumping box is used to permit the box to be tilted to discharge its contents.

With these and other objects and advantages in view, this invention consists in a riding toy having a movable seat, flexibly or pivotally connected with some portion of the toy structure, whereby the seat may be raised and lowered and may always be returned to a definite position with respect to the steering handle of the toy. The invention further consists in the several novel features hereinafter fully set forth and claimed.

The invention is clearly illustrated in the drawing accompanying this specification, in which,

Fig. 1 is a perspective view of a riding toy embodying a simple form of the present invention;

Fig. 2 is a detail, fragmental section showing the pivotal connection for the seat and

Fig. 3 is a horizontal section taken on the line 45 3—3 of Fig. 2.

Referring to said drawing, which is illustrative of one embodiment of the invention, the reference characters 4, 4, designate the sills or frame members of the frame 5, supported by wheels 6, 7 and desirably having structures simulating an automobile hood 8, a cab 9 and fenders 10, mounted on their forward ends. The front wheels 6 are usually mounted on an axle member 11 swiveled to a cross bar 12 fastened to the front of the frame members and connected by a link 13 and

lever 14 to a steering rod 14 rotatively mounted in the cab 9 and provided on its upper end with a steering handle 15 whereby the front wheels may be guided in steering the toy. This exact form of steering mechanism shown is not necessary as any well known steering device may be substituted therefor.

Mounted on the rear end of the frame is a truck box 16 which may be used to transport loads of any kind. The box may be fixedly mounted on the frame, but in order to make the toy more attractive, it has been tiltably mounted thereon, whereby the contents thereof may be dumped therefrom. As shown, the box is of rectangular form and is supported above the frame 5 by an inverted U shaped bracket 17, riveted, spot welded or otherwise fastened to the bottom of the box, the two arms of the bracket being apertured at their lower ends to receive the axle 18 for the rear wheels. Desirably a cross brace 19 fastened to the frame members 4 has downwardly bent apertured ears 19a through which the rear axle extends. To the bottom of the forward end of the box is secured a yoke like bracket 20 which normally rests upon the frame and supports the forward end of the box. For the purposes of obtaining strength and rigidity, the upper edges of the sides 21 of the box are flanged outwardly as at 22. It will be understood that the box may be tilted upward on the rear axle as a fulcrum to discharge the contents of the box.

The riding seat shown at 23, is supported above the box by a yoke like bracket 24, spot welded or otherwise rigidly fastened to the underside of the seat and having downwardly projecting arms 25 that are arranged to rest upon the flanged upper edges of the box. Desirably the lower ends of the arms 25 are formed with Z or reverse bends 26 that straddle the flanged edges of the box sides and thereby rigidly hold the seat in place. It is to be observed that the arms 25 rest upon the box at places intermediate its points of support on the frame. As a result the seat tends to hold the box down on the frame.

Projecting forwardly from the seat is an arm 27 which is pivotally connected with some part of the toy structure whereby the seat may be swung away from the box. In its present form the seat arm 27 is shown as pivotally mounted on the cab 9 by means of ears 28 spot welded or otherwise fastened to the back wall 29 of the cab and a pin 30 which extends through apertures in the ears and seat arm. Desirably the seat and its arm are formed from a piece of struck up

sheet metal and for the purpose of strength and rigidity a downwardly projecting flange 31 is formed along the margin of the seat and its arm. While the exact shape of the seat is not material to the invention, broadly considered, it is shown as of oval form with its major axis extending cross-wise of the toy and with its forward edge merging into the side edges of the arm, so as to provide a comfortable seat for the child.

10 The seat may be tilted upward when desired so as to uncover the box, whereby the box may be conveniently loaded and unloaded, and if a dumping box is employed, the latter may be dumped when the seat is raised. By reason of the pivotal connection between the seat and toy structure the seat remains permanently connected with the toy structure and therefore cannot become lost or mislaid. Furthermore, the connection between the seat and toy structure always locates the seat at the proper distance away from the steering handle to enable the child to sit with comfort on the seat and conveniently reach the handle. The possibility of placing the seat behind the fulcrum of the box on the frame, which might 25 cause slight mishaps, is also made impossible.

While the invention has been shown and described in connection with a toy, simulating an automobile dump truck, I do not wish to limit myself to this type of toy, as various wheeled toy vehicles will readily suggest themselves to those skilled in the art in place of the one shown. Furthermore the seat may be pivotally mounted on any suitable part of the toy in such manner as to be readily swung back to uncover the box.

I claim as new and desire to secure by Letters Patent:

1. A wheeled toy having a frame with a tiltable dumping box mounted thereon, and a movable riding seat, pivotally mounted on an element of the toy, said seat being arranged to rest on the box and adapted to be swung upward therefrom to permit the box to be tilted.

2. A wheeled toy comprising a frame, front steering wheels and rear wheels supporting the frame, a cab mounted on the frame, a steering handle and connections between the steering handle and steering wheels, a box mounted on the frame, and a riding seat resting on the box and pivotally connected to the cab, whereby the seat may be raised above the box to permit ready access thereto.

3. A riding toy comprising a wheeled structure provided with a box having flanged sides, a riding seat having a bracket provided with downwardly extending arms arranged to rest on the flanged sides of said box, and an arm projecting from said seat and pivotally mounted on the wheeled structure, whereby the seat may be raised above the box to permit ready access thereto.

4. A riding toy comprising a frame, front steering wheels and rear wheels supporting said frame, a steering handle for the steering wheels, a dumping box, and a riding seat adapted to rest upon the box and pivotally mounted on a member of the toy, whereby the seat may be raised above the box to permit the same to be tilted.

CLEMENT E. THOMPSON.
